UNITED STATES PATENT OFFICE.

ARMIN GEORGE KESSLER, OF BUFFALO, NEW YORK, ASSIGNOR TO FARREL FOUNDRY AND MACHINE CO., INC., OF BUFFALO, NEW YORK, A CORPORATION OF CONNECTICUT.

FLUID-CIRCULATING PLATE.

Application filed August 20, 1925. Serial No. 51,374.

This invention relates to improvements in fluid-circulating plates, such plates being particularly employed in hydraulic presses for vulcanizing and similar uses.

5 One of the objects of the invention is to improve the construction of such plates with a view of obtaining an unrestricted circulation of water, steam or other fluid therethrough and thus rendering them more 10 efficient in operation.

Another object is the provision of a channeled or ported plate of this character having simple and inexpensive means for plugging between the channels at predetermined 15 points to cause a proper diversion of the circulating fluid in a more or less circuitous course through the entire area of the plate.

A still further object of the invention is to provide a fluid circulating plate which 20 is so constructed and organized that its channels can be readily and thoroughly cleaned out in a minimum period of time.

In the accompanying drawings:

Figure 1 is a front elevation of a hydraulic press equipped with my improved 25 circulating plates. Figure 2 is a top plan view, partly in section, of one of the plates. Figure 3 is a cross-section thereof on line 3-3, Fig. 2. Figure 4 is a fragmentary 30 cross section thereof on line 4-4, Fig. 2. Figure 5 is a sectional top plan view of a modified form of the invention. Figure 6 is a cross section thereof on line 6-6, Fig. 5. Figure 7 is a fragmentary horizontal section of another modification of the 35 invention.

Similar characters of reference indicate corresponding parts throughout the several views.

40 By way of example, the improved plates are shown in connection with a hydraulic press of any well-known construction, that illustrated in Fig. 1 of the drawings comprising a cylinder 10, a ram 11, guide-posts 12 and upper and lower cross heads 13, 14, respectively. The circulating plates, designated generally by the numeral 15 and of which three are shown, are applied to the upper and lower cross heads in the usual 45 manner and the intermediate one is suspended from the customary guide rods 15a.

In the preferred embodiment of the invention shown in Figs. 1-4, inclusive, each plate 15, which is rectangular in plan, is 50 made of rolled steel and is provided with

a plurality of angular or L-shaped fluid circulating channels composed of parts or branches 16, 17. The branches 16 of these channels are substantially parallel with one another and are drilled from one edge of 60 the plate toward the opposite edge, while the companion branches 17 are likewise parallel with one another and drilled from the adjoining edge of said plate toward the opposite edge, the inner or closed ends of 65 companion channel-branches communicating with each other and meeting approximately on a diagonal line drawn from the lower left hand corner to the upper right hand corner of the plate, as shown in Fig. 2. 70 In other words, the branches of the angular channels are of progressively increasing length from one corner of the plate toward the diagonally-opposite corner.

After the drilling of these channels is 75 completed, their open ends are tapped and fitted with suitable plugs 18.

For the purpose of establishing communication between the several channels 16, 17 to provide a circuitous course for the fluid 80 through the same, their outer ends are intersected by connecting or cross passages 19, 20 formed by drilling holes in the plate at right angles to the corresponding channel-branches 16, 17. The inner ends of said 85 cross passages terminate at the outermost channel, while their outer ends are tapped and fitted with suitable plugs 21. Extending across the passages 19, 20 in the alternate spaces between the channel-branches 16 90 and 17 are filler pieces or plugs 22 which prevent the direct flow of the fluid through the passages and divert it through the channels so that the fluid passes successively from one channel to an adjoining one through 95 the interconnecting unplugged portions of the passages. As shown in Fig. 2, the filler pieces located at the lower edge of the plate between the channel-branches 17 are disposed alternately or in staggered relation 100 with respect to those located at the side edge of the plate between the channel-branches 16, whereby the fluid is compelled to take a sinuous course, as indicated by 105 the arrows shown in said figure. Leading into the outermost or longest channel is a fluid inlet 23 and opening into the innermost or shortest channel is a fluid outlet 24. A tubular member or sleeve 25 extends across 110 the passage 20 into such innermost channel

for plugging the corresponding end of said passage. This sleeve is provided in the side thereof facing the companion passage 19 with a port 26 through which some of the fluid is discharged after being circulated through the plate, as indicated by the arrows in Fig. 2.

As shown in Fig. 4, the filler pieces or plugs 22 which cause the proper diversion of the fluid through the circulating channels may be somewhat larger in diameter than the latter and are inserted in corresponding drilled openings or sockets 27 having internally-threaded counter-bores 28 for receiving set screws 29 which hold the plugs in place. The latter are preferably constructed of brass or other non-corrosive metal.

By this arrangement of the fluid-conducting channels and connecting passages, they effectively cover the entire area of the plate and insure a uniform distribution of the heating or cooling fluid thereover.

This method of drilling the circulating plate is a very simple and inexpensive one and results in an absolutely free flow of the fluid through the circulating channels. Furthermore, the method of plugging between the channels to cause the diversion of the fluid in a sinuous course over the entire plate-area is exceedingly simple and the plugs 18, 21 and 22 are readily removable to permit of thoroughly cleaning out the channels, when desired.

In the modified form of the invention shown in Figs. 5 and 6, the plate 30 is provided with a plurality of parallel circulating channels 31 formed by drilling through the plate from one edge thereof to the opposite edge and closed at their ends by suitable screw plugs 32. At their ends, these channels are intersected by passages 33 closed at their ends by screw plugs 34. Extending across these passages in the alternate spaces between the circulating channels are filler pieces or plugs 35 held in place by set screws 36. The filler pieces in the one passage are staggered with respect to those in the other passage, whereby the fluid is caused to be circulated in a sinuous course indicated by the arrows in Fig. 5. The outermost channel 31 at one side of the plate has a fluid inlet 37 while the corresponding channel at the opposite side of the plate has a fluid outlet 38.

Another form of plugging the alternate spaces between the circulating channels 31 is shown in Fig. 7, wherein babbitt or other material 38 is poured into such spaces through openings 39 and hammered in place, after which the openings are fitted with suitable screw plugs 40.

I claim as my invention:

1. A circulating plate of the character described, provided with a plurality of spaced fluid-circulating channels having a common inlet and a common outlet and passages intersecting said channels near their ends, said channels and said passages being formed by drilling holes in the plate, plugs fitted in the ends of the channels and passages, and filler-pieces extending across said passages and disposed in the alternate spaces between said channels, whereby the fluid is diverted in a sinuous course therethrough. 75

2. A fluid-circulation plate of the character described, having a plurality of angular channels, the parts of which extend inwardly from adjoining edges of the plate and connecting passages intersecting said several channels, and fluid-diverting means in said 80 passages between certain of said channels, the diverting means in the passage at one edge of the plate alternating with the diverting means in the passage at the adjoining edge to cause a sinuous flow of the fluid 85 through the channels and passages.

3. A fluid-circulation plate of the character described having a plurality of angular channels, the parts of which extend inwardly from adjoining edges of the plate and connecting passages intersecting said several channels, and removable plugs arranged 90 transversely in said passages between certain of said channels, the plugs in the passage at one edge of the plate alternating with the 95 plugs in the passage at the adjoining edge.

4. A fluid-circulation plate of the character described, having a plurality of angular or L-shaped channels, the parts of which extend inwardly from adjoining edges of the 100 plate and connecting passages intersecting the outer portions of said channels, the parts of said angular channels being of progressively increasing length from one corner of the plate toward its diagonally opposite corner. 105

ARMIN GEORGE KESSLER.
